Primary Examiner — Susan E Krakower*Assistant Examiner* — Ramzi Almatrahi(74) *Attorney, Agent, or Firm* — Samuel M. Korte; Max M. Ali(57) **CLAIM**

The ornamental design for a camera device, as shown and described.

DESCRIPTION

FIG. 1 is a front perspective view of a camera device according to the present invention;

FIG. 2 is a rear perspective view of the camera device;

FIG. 3 is a top view of the camera device;

FIG. 4 is a front view of the camera device;

FIG. 5 is a bottom view of the camera device;

FIG. 6 is a rear view of the camera device;

FIG. 7 is a left side view of the camera device; and,

FIG. 8 is a right side view of the camera device.

The broken lines shown in FIGS. 1 through 8 represent portions of the camera device that form no part of the claimed design. The "GARMIN" trademark depicted in the drawing figures is a trademark of Garmin Ltd. or its subsidiaries and it forms no part of the claimed design.
